UNITED STATES PATENT OFFICE.

ALEXANDER WINTON, OF LAKEWOOD, OHIO.

PROTECTING MEANS FOR VESSELS.

1,337,809.

Specification of Letters Patent. Patented Apr. 20, 1920.

Application filed June 22, 1917. Serial No. 176,322.

To all whom it may concern:

Be it known that I, ALEXANDER WINTON, citizen of the United States, residing at Lakewood, in the county of Cuyahoga and State of Ohio, have invented certain new and useful Improvements in Protecting Means for Vessels, of which the following is a specification.

This invention relates to the protection of boats or other vessels against hostile craft, particularly submarine boats.

The object of the invention is to provide means connected to the vessel or boat to be protected, hereinafter termed the mother vessel, and which can lie at some distance therefrom, said means carrying an explosive charge to destroy any target, such as a hostile submarine or other object, with which it may come in contact. More specifically the object of the invention is to provide an improved form of torpedo suitably arranged so that one or more thereof can be connected to the mother vessel, and when said vessel is traveling through the water will keep abreast thereof and destroy any submarine or other hostile craft or object attacking the mother vessel.

Further objects of the invention will be in part obvious and in part will appear more in detail as hereinafter.

In the drawings, which represent one embodiment of the invention, Figure 1 is a diagrammatic view illustrating the mother vessel and two torpedoes embodying the invention connected thereto; Fig. 2 is a side elevation of one form of torpedo embodying the invention, and Fig. 3 is a plan view thereof; partly broken out and in section to expose the interior parts.

In protecting vessels against hostile attacks it has been proposed to guard the vessel by screens or other devices attached to the vessel and spaced therefrom, but such guards can not be spaced at a very great distance from the vessel, and, consequently, even if carrying an explosive charge could not reach a hostile attacking vessel unless within a very close range of the mother vessel. As hostile vessels usually attack the mother vessel from one side or the other it is therefore desirable to provide the mother

vessel with some means spaced laterally away from the mother vessel on one or both sides to thread the adjacent waters and destroy submarines or other vessels approaching within reasonable range on either side. The means employed in the present invention is a suitable form of torpedo together with proper means for keeping it abreast of the mother vessel.

The torpedo itself may be of any desired form and equipped with the simplest kind of mechanism for carrying out its proper functions. The torpedo shown in the drawings has the usual shell or casing 1, whose head end 2 carries an explosive charge fired by contact of the war head 3 with a hostile object. At the rear of the shell is located a propeller 4 of the usual form and supported by an operating shaft 5 extending longitudinally along the torpedo axis, 6 represents the forward horizontal level controlling planes and 7 the adjustable rearward plane or planes. The torpedo will be ballasted and the horizontal planes set in the usual manner so as to cause it to float or travel either on the surface of the water or uniformly at a definite level of submergence therein, as will be readily understood.

The torpedo is also provided with suitable means whereby it derives motion of propulsion from the mother vessel so as to keep it abreast thereof and protect it from laterally adjacent hostile objects. As shown, the torpedo is provided with a through water passage 8, preferably of Venturi form. In other words, said passage has a wide inlet or mouth 9 and walls 10 gradually converging to a more restricted waist 11 beyond which it rapidly enlarges to the outlet 12.

The inlet 9 is on one side of the torpedo, specifically that side toward the mother vessel, and the outlet 12 is on its opposite side. In the passage 8 and preferably located at or in advance of the restricted waist 11 are located one or more water power wheels 13 attached to the propeller shaft 5, which passes through one of the walls of the water channel and at its forward end is journaled in a bracket 14 carried by the other wall. This water wheel 13, of which three are shown for purpose of illustration, may be similar

in form to the usual torpedo propeller, with the inclination of its vanes in the same direction.

Any suitable connection may be provided 5 between the torpedo and the mother vessel, said connection being preferably of flexible light form to reduce the water friction and illustrated as a wire cable 15 attached at one end to one side of the mother vessel and at 10 its opposite end suitably connected to the near side of the torpedo in advance of its center of mass. Specifically, the outer end of the cable 15 is attached to an eye in the torpedo 16 projecting outwardly at the 15 mouth 9 from the advance wall 10 and in the water channel.

The action is as follows:

Fig. 1 illustrates the mother vessel and 20 two torpedoes, one on either side thereof, although it will be understood that a larger number of torpedoes can be connected to the same mother vessel. In this view, the vessel and torpedo are shown out of true proportions for clearness of illustration, the vessel 25 being reduced and the torpedoes being enlarged from their true sizes.

When the vessel is traveling along a straight course, such as indicated by the line A—A, the two torpedoes stand out at 30 the sides and are abreast of said vessel but with their longitudinal axes diverging forwardly therefrom, thereby exposing to the water along their lines of advance $a-a$ and $a'-a'$ the inlets or mouths of the two torpedoes. The latter are respectively a right 35 and a left, in that their water passages are inclined diagonally from front to rear and side to side in opposite directions. As a result of the Venturi principle the convergence of the walls 10 of the water passages produces pressure at the restricted waist 11 in each torpedo, thereby supplying power 40 to turn the power wheel 13 which rotates the propeller 4. The form and size of the power 45 wheel and propeller together with the configuration of the Venturi passage and weight of the torpedo are important and are adjusted and designed so that the Venturi passages furnish sufficient power at all times to 50 propel the torpedo through the water, causing it to advance and keep abreast of the mother vessel notwithstanding the fact that it is connected thereto merely by a flexible cable. In practice it is found that the cable 55 15 will stand out nearly at right angles to the course of the vessel.

When the vessel changes course either to the right or left the torpedo still keeps its position abreast of the vessel. In other 60 words the torpedo on the outside of the curved course of the vessel advances to increase its speed to make the longer course in the same time as the vessel makes the shorter course, while the torpedo on the 65 inner side of the curve lags back or is re-

tarded so as to keep back to its place. This action may be explained as follows:

Let us say that the vessel turns to the right in Fig. 1, to or toward the diagonal course B—B. In this case the torpedo X at 70 the left has apparently lost some position and is behind the mother vessel. However, the line of travel of the torpedo through the water is now the line $b-b$ and the torpedo is subject to an increased pull of the cable 75 15 to drag it out from its course $a-a$ and into the new course $b-b$. The result is to expose a larger effective area of the inlet 9 to the water along the new course $b-b$. Consequently a greater quantity of water 80 flows through the water passage and a greater pressure is produced at the restricted waist 11. This increases the power supply 85 of the water wheel and speeds up the propeller to advance the torpedo more rapidly 90 through the water. Actually, when the vessel turns, the torpedo on the outside of the curve speeds up immediately and advances with the vessel to the position indicated by the dotted lines at the left in Fig. 1 and 95 keeps abreast of the vessel all the way around the curve.

In view of the foregoing, the effect on the torpedo on the inside of the curve will be more readily understood. Let us assume 95 now that the vessel in Fig. 1 turns to the left or toward the new course C—C. In this case the torpedo has apparently gained in position and is in advance of its proper place. However, the pull on the cable 15 100 has been slackened and the axis of the torpedo is already more closely in line with its new course $c-c$. The result is to reduce the effective area of the mouth 9 exposed to the water along the line of direction of the new 105 course, to decrease the power at the wheel 13 and to retard the propeller so that the torpedo lags back and maintains its position 110 abreast of the vessel.

Having described the action of the torpedo at the left in Fig. 1 on both the outside and inside of the curve, the action of the torpedo at the right will require no description, as it acts in the same manner, merely differing from the one described in 115 that it is a right instead of a left.

It will now be readily understood that the effect of the arrangement described is for the torpedo to reach and maintain a balanced position. Should the torpedo actually 120 or apparently gain in position on the mother vessel the effective area of its mouth to the water is reduced, its power decreases and it drops back. Should it actually or apparently lose in position the exposed area is increased and it speeds ahead.

The invention provides simple means at low cost capable of threading a wide area of water at the sides of the advancing vessel, and destroying any hostile object within 130

reasonable distance from the vessel. The length of the connecting cable 15 depends only on the power of the mother vessel and the greater or less water friction effect produced by the length of cable employed.

5 What I claim is:

1. A towed torpedo carrying an explosive charge and provided with a passage through which water flows as the torpedo travels 10 through the water, and propelling means for said torpedo actuated by the flow of water through said passage.

2. A torpedo carrying an explosive charge and provided with a water passage extended 15 horizontally therethrough along a diagonal line from side to side.

3. A torpedo carrying an explosive charge and provided with a water passage extended horizontally therethrough, and propelling 20 means therefor actuated by the flow of water through said passage.

4. A torpedo carrying an explosive charge and provided with a water passage extended horizontally therethrough along a diagonal 25 line from side to side, and propelling means therefor actuated by the flow of water through said passage.

5. A torpedo carrying an explosive charge and provided with a diagonally extended 30 water passage therethrough whose walls converge toward a restricted waist.

6. A torpedo carrying an explosive charge and provided with a diagonally extending water passage therethrough whose walls converge toward a restricted waist, and means 35 at said restricted waist arranged to utilize the water pressure for propulsion of the torpedo.

7. A torpedo carrying an explosive charge 40 and provided with a water passage therethrough, propelling means for said torpedo actuated by the flow of water through said passage, and towing means for connecting said torpedo to a mother vessel.

45 8. A torpedo carrying an explosive charge provided with a water passage extending horizontally therethrough, and towing means for connecting said torpedo to a mother vessel.

50 9. A torpedo carrying an explosive charge and provided with a water passage extending horizontally therethrough, along a diagonal line from side to side, and means for connecting said torpedo to a mother vessel.

55 10. A torpedo carrying an explosive charge and provided with a water passage extending horizontally therethrough, propelling means therefor actuated by the flow of water through said passage, and means 60 for connecting said torpedo to a mother vessel.

65 11. A torpedo carrying an explosive charge and provided with a water passage extending horizontally therethrough along a diagonal line from side to side, propelling

means therefor actuated by the flow of water through said passage, and means for connecting said torpedo to a mother vessel.

12. A torpedo carrying an explosive charge and provided with a diagonally extending 70 water passage therethrough whose walls converge a restricted waist, and means for connecting said torpedo to a mother vessel.

13. A torpedo carrying an explosive charge and provided with a diagonally extending 75 water passage therethrough whose walls converge a restricted waist, means at said restricted waist arranged to utilize the water pressure for propulsion of the 80 torpedo, and means for connecting said torpedo to a mother vessel.

14. A torpedo carrying an explosive charge and provided with a water passage therethrough, propelling means for said tor- 85pedo actuated by the flow of water through said passage, and a flexible cable for connecting said torpedo to a mother vessel.

15. A torpedo carrying an explosive charge and provided with a water passage 90 extending horizontally therethrough along a diagonal line from side to side, and a flexible cable for connecting said torpedo to a mother vessel.

16. A torpedo carrying an explosive 95 charge and provided with a water passage extending horizontally therethrough along a diagonal line from side to side, and a flexible cable for connecting said torpedo to a mother vessel.

17. A torpedo carrying an explosive charge and provided with a water passage extending horizontally therethrough, propelling means therefor actuated by the flow of water through said passage, and a flexible 105 cable for connecting said torpedo to a mother vessel.

18. A torpedo carrying an explosive charge and provided with a water passage extending horizontally therethrough along 110 a diagonal line from side to side, propelling means therefor actuated by the flow of water through said passage, and a flexible cable for connecting said torpedo to a mother vessel.

115 19. A torpedo carrying an explosive charge and provided with a diagonally extending water passage therethrough whose walls converge toward a restricted waist, and a flexible cable for connecting said tor- 120pedo to a mother vessel.

20. A torpedo carrying an explosive charge and provided with a diagonally extending waterpassage therethrough whose walls converge toward a restricted waist, 125 means at said restricted waist arranged to utilize the water pressure for propulsion of the torpedo, and a flexible cable for connecting said torpedo to a mother vessel.

21. In combination, a mother vessel, a tor- 130

pedo, a flexible cable for connecting the torpedo to the vessel, a torpedo propeller, said torpedo being provided with a water passage, and means whereby the flow of water through said passage actuates the said propeller.

22. In combination, a mother vessel, a torpedo, a flexible cable for connecting the tor-

pedo to the vessel, a torpedo propeller, said torpedo being provided with a water passage, said passage having walls converging to a restricted waist, and a water wheel located at said waist operatively connected to said propeller.

In testimony whereof I affix my signature. 15
ALEXANDER WINTON.
